UNITED STATES PATENT OFFICE.

ALFRED A. LOVEJOY, OF SOUTH BEND, INDIANA.

SEESAW.

Application filed November 14, 1924. Serial No. 749,888.

This invention relates to improvements in see-saws and has particular reference to such as are adapted for use by a single person,—one object of the invention being to so 5 construct a see-saw that it may be readily adjusted for use of persons differing in height or differing in weight.

A further object is to construct the device in such manner that adjustment of the board 10 for different weights or heights of persons may be effected without materially changing the normal angle of inclinations of the board or see-saw per se.

With these and other objects in view, the 15 invention consists in certain novel features of construction and combinations of parts as hereinafter set forth and pointed out in the claims.

In the accompanying drawings,—
20 Figure 1 is a view partly in elevation and partly in section showing an embodiment of my invention, and

Figure 2 is a plan view partly broken away.

25 My improved see-saw structure includes a base frame 1 which may be provided with rubber knobs or feet 2 located adjacent to respective ends thereof. Secured upon the base frame 1 near respective sides thereof and in proximity to one end, are plates or bars 3—3, each having elongated slots 4. The base portion of standards 5 are located upon the plates or bars 3 and are adjustably secured to the latter by means of headed screws 6 and thumb nuts 7, whereby said standards may be adjusted in directions parallel with the longitudinal axis of the base frame 1 for a purpose hereinafter explained.

The see-saw board is shown at 8 and has 40 secured to its under face to one side of the longitudinal center of the board, a bearing plate 9,—one of such bearing plates being located in proximity to each side edge portion of the board. The bearing plates 9 are provided with elongated slots 10 for the passage of headed screw bolts 11, said bolts also passing through the board 8 and receiving thumb nuts 12 at their lower ends, washers 13, being located between said thumb nuts and the under faces of the plates 9. The plates 9, which are thus adjustable relatively to the board, are provided intermediate of their ends with depending perforated enlargements 14. Vertically disposed, threaded bars 15 pass through the upper portions 16 of the standards 5 and

through cross-bars 17 in said standards and are retained at any desired vertical adjustment by means of nuts 18 and 19. The threaded bars 15 are provided at their upper ends with perforated heads 20 which align with the perforations of the depending enlargements 14 for the passage of a transversely disposed fulcrum rod 21, and in this manner the see-saw board is pivotally 60 supported upon the vertical threaded bars 15. An eye 22 is secured to the board 8 near the forward end thereof and to this eye one end of a counter-balancing spring 23 is attached. The lower end of this spring has 65 secured thereto a nut 24 through which a screw 25 passes, said screw also passing through the base 1 and having a head 26 at its lower end countersunk into the said base frame, and a clamping nut 25^a is located on 70 said screw and engages the upper face of the base frame 1. The rear end portion of the board 8 provides a seat 27, for which a back and hand hold 28 is provided.

The base 29 of a post 30 is secured upon 80 the board 8 in front of the seat portion 27 thereof and to the upper end portion of this post a handle bar 31 is clamped or otherwise secured. The board is also provided forwardly of its seat portion with stirrups 85 or foot rests 32.

With my improvements the see-saw board 8 may be readily adjusted through the medium of the vertical threaded bars 15 to accommodate children of different heights 90 and when thus adjusted, the connection of the spring 23 with the base frame may also be adjusted so as to maintain the proper angle of inclination for the board. By adjusting the standards 5 and their connections with the base frame and the board 8 in directions toward one or the other end of the frame and board, the latter may be adapted for use of children of different weights without necessity of changing the 100 tension of the counterbalancing spring 23 and without changing the angle of inclination of the board to an appreciable extent. To avoid changing the angle of inclination to any extent when the adjustments above 105 mentioned are made, the connection of the spring with the base frame may be slightly adjusted.

Having fully described my invention what I claim as new and desire to secure by Letters-Patent, is:

1. In a see-saw, the combination of a base

- member, bars secured on the base longitudinally thereof and provided with longitudinal slots, standards resting on said bars, fastening devices carried by the lower ends of the standards and engaged through the slots in said bars, threaded bars fitted in the standards to be adjusted vertically, a see-saw board, plates secured to the bottom of the see-saw board and adjustable longitudinally thereon, pivot connections between said plates and the upper end of the threaded bars, and a spring connection between one end of the see-saw board and the base member.
- 15 2. In a see-saw, the combination with a base member, and a see-saw board, of bars secured on the base and disposed longitudi-

nally thereof, standards resting on said bars, means for securing the standards to the bars at selected points in the length of the bars, threaded bars fitted in the standards to be adjusted vertically, slotted plates adjustably secured to the see-saw board, pivot connections between said slotted plates and the vertically adjustable bars, and a spring between one end portion of the board and the base member, the connection of the spring with one of said parts being adjustable in the direction of the length of the spring.

In testimony whereof, I have signed this specification.

ALFRED A. LOVEJOY.
